United States Patent Office

Des. 197,688
Patented Mar. 10, 1964

197,688

PHOTOFUOROGRAPHIC CAMERA

Edgar J. Bastin, 685 Sperry Road, Chesterland, Ohio

Filed June 17, 1963, Ser. No. 75,386

Term of patent 14 years

(Cl. D83—1)

FIG. 1

FIG. 2

FIGURE 1 is a perspective view of the top and one side of a photofluorographic camera showing my new design; and,

FIGURE 2 is a perspective view of the bottom and second side thereof.

The essential features of my design are shown in full lines.

I claim:

The ornamental design for a photofluorographic camera, as shown and described.
